UNITED STATES PATENT OFFICE

2,605,856

DEAERATING SYSTEM FOR WATER OR
STEAM CONDENSATE

Alton Kirkpatrick, Boston, Mass., and Harry H. McMeen, Harvey, Ill., assignors, by mesne assignments, to the United States of America as represented by the United States Atomic Energy Commission

Application July 2, 1947, Serial No. 758,542

4 Claims. (Cl. 183—2.5)

1

Our invention relates to cooling systems and more particularly to the type of cooling system employing deaerating equipment for the removal of gases and/or other impurities in gaseous form from the liquid or circulating medium of the system.

In the operation of production equipment used in connection with the electromagnetic process of particle separation at high potentials and under conditions where large power consumption is involved, and where a part of the power is converted into heat energy, it becomes necessary to circulate a cooling medium, such as water, through the walls and heated parts of the apparatus to prevent overheating of or injury to such parts. Due to the high operating potentials of this equipment and to the fact that the lead line for the cooling liquid is ordinarily maintained at or near ground potential, it is customary to employ lap coils of insulated material, such as porcelain, to join the lead lines to the high potential elements of the equipment. Under these circumstances it is necessary that the cooling medium also be a good insulator with a minimum ionization and low conductivity to prevent leakage between the elements and the lead lines through this liquid. To accomplish this result, the liquid or medium is deaerated to remove air and such gases as CO_2 (carbon dioxide) which react with the medium when water is used, to produce carbonic acid, the reaction being:

The carbonic acid ionizes and causes the medium to conduct. Other gases which produce a similar effect must also be eliminated. In this connection, it was found that oxygen carried by the water would attack and oxidize steel piping used in the system, creating oxides and hydroxides which would ionize and increase the conductivity of the liquid, or that the oxygen would react with the impurities to release elements which would react with others to form salts with the same effect upon conductivity.

The deaerating of liquids to remove air and undesirable gases to reduce corrosion has been known to the prior art. Examples of such systems may be found in the patents to Elliott, 1,457,153; McDermet, 1,742,998; and Gibson, 1,969,888. These structures, however, fall to make provision for a storage reservoir and a deaerating chamber, both under vacuum to obviate the possibility of gases entering or being absorbed by the liquid. Additionally, they fail to take into account the necessity for creating sufficient liquid

2

pressure within the apparatus to supply the circulating pumps with liquid at a pressure above that of the surrounding atmosphere.

Applicants with a knowledge of these problems of the prior art have for an object of their invention the provision of a liquid cooling system for electric process equipment which will remove objectionable gases from the liquid to maintain the high electrical resistance thereof.

10 Applicants have as another object of their invention the provision of a deaerating system where both the storage reservoir and the deaerating chamber are maintained under vacuum to prevent the cooling liquid from reabsorbing gases from or in the air.

Applicants have as another object of their invention the provision of a system employing a contact vacuum deaerator located at an elevation above the pumping arrangement for circulating liquid through the system in order to build up a pressure therein to overcome the action of the vacuum in the deaerating chamber, thus avoiding the possibility of leakage of air through numerous system connections.

20 25 Applicants have as a further object of their invention the provision of a system with a deaerator having the storage tank and deaerator chamber in a single vessel and in communication with each other to facilitate evacuation and removal of undesirable gases.

Applicants have as a further object of their invention the provision of a system with a deaerator having a storage tank which automatically feeds liquid to the system when the height of liquid in the deaerator section falls below a predetermined level.

30 35 40 Applicants have as a still further object of their invention the provision of a liquid circulating system for deaeration of liquids with pressure control in the return line feeding the deaerator to maintain constant circulation of liquid in the process piping, in the event the vacuum falls below a predetermined level.

45 Other objects and advantages of our invention will appear from the following specification and accompanying drawing and the novel features thereof will be particularly pointed out in the annexed claims.

In the drawing, the sole figure is a schematic diagram of our improved system showing the deaerator in section.

50 Referring to the drawing in detail, 1 designates a contact type vacuum deaerator in the form of an upright cylindrical tank divided into an upper deaerating chamber 5 having an active liquid

storage space in the lower portion thereof, and into a lower inactive liquid storage reservoir 3, separated by a diaphragm 4, through which an overflow pipe 12 passes and whose upper end terminates in a hood 13. The pipe 12 also serves to provide communication between the reservoir 3 and the chamber 5 to maintain the reservoir under vacuum. Positioned at a level below the deaerator is a circulating pump 2 which is connected to the lower part of chamber 5, below the usual liquid level thereof, by a line 14. The pump 2 is then connected by line 16, through the process cubicles 17 to the coolers 18. They discharge cooled liquid through line 19 into the upper end of the deaerator tank 1 and chamber 5 through the end of pipe 10 into a tray or trough 20 which continually overflows so that liquid therefrom passes down through a honeycomb or lattice work or over a set of overlapping baffles such as 21. The liquid cascades over the surfaces of the baffles or slats and gives off oxygen, carbon dioxide and other gases absorbed therein.

Vacuum is created in connecting chambers 5 and 3 through line 22, which may be connected to conventional vacuum equipment, preferably a steam ejector 23 supplied with steam from line 24 which discharges liquid through line 40 to reservoir 3. The lower extremity of reservoir 3 feeds into line 14 through line 26 containing pressure valve 9 controlled from line 27 which leads to chamber 5 so that when the water level in the chamber falls below a predetermined point 8, the operation of the float valve 41 through a lever or pressure medium opens valve 9 permitting water to flow from storage reservoir 3 through line 26 and valve 9 into line 14 and into the system.

In the operation of the system pump 2 operates under pressures at or slightly above atmospheric in line 14 due to the static head of liquid in line 14 being in excess of the vacuum in chamber 5 created by the steam vacuum system 23. In order to overcome the effect of the steam vacuum system on the flow of liquid in line 14 and to aid the pump 2 in its operation, tank 1 is preferably placed at some elevation above pump 2 in order to build up a pressure at the inlet of pump 2.

Liquid flowing through line 14 and pump 2 feeds into the process cubicles 17 through line 16, thence through closed coolers 18 in order to lower its temperature and dissipate the heat absorbed from the process cubicles 17. While the coolers 18 may be of usual design, they are preferably of a type which do not expose the liquid to the atmosphere where it might absorb air or undesirable gases. Any type of heat transfer unit where the heat is transferred to a secondary cooling liquid which passes over tubes through which the primary cooling liquid passes, is preferable. The secondary liquid may be cooled by a cooling tower, which causes evaporation, or by spraying or otherwise as may seem most practicable.

On leaving the coolers 18, the cooled liquid is returned through line 19 to the upper end of tank 1. Connecting line 14 with line 19 is line 29 containing pressure valve 11 controlled from line 28 which is in turn joined to line 19. In the event of a decrease in vacuum in the deaerator a higher pressure will be created in line 28 which is communicated to valve 11 causing it to open and permitting recirculation of liquid to pump 2, thus insuring the supply of cooling water to process.

Where the tank 1 is at a considerable elevation above pump 2, such pump may not develop sufficient pressure to return the liquid to the top of tank 1 in case vacuum is lost in the deaerator. The resulting increase in pressure created in line 28 will open valve 11 thus relieving the pressure on pump 2 and maintaining flow of cooling liquid to process, as described in the foregoing.

To initially supply water to the system and replace water used or lost during operations, a supply main 30 feeds into line 19. Flow of water through main 30 to line 19 is controlled by pressure valve 31 through float operated valve 32 for controlling the pressure applied through line 33 to valve 31. Float valve 32 is connected to storage reservoir 3 through lines 34, 35 and is responsive to water level in that reservoir for controlling the operation of valve 31. On the other hand, water may be removed from the system through line 36 and three-way valve 37. The line 24 may also be drained into the reservoir 3 through line 42 by opening valve 43.

Having thus described our invention, we claim:

1. A deaerating system of the character described comprising a container, a diaphragm positioned across said container dividing it into an upper and a lower chamber, a baffle arrangement positioned intermediate of said upper chamber for the passage of liquid to remove entrained gases, means for removing liquid from one extremity of said upper chamber for circulation through a system including heat exchange units and for returning the liquid to the other extremity of the chamber, said lower chamber serving as a liquid storage reservoir, means for connecting said reservoir into the circulating system, means responsive to liquid level in said upper chamber for regulating the flow of liquid from the reservoir to the system, and means for placing the upper and the lower chamber under vacuum pressure.

2. A deaerating system of the character described comprising a container, a partition for dividing the container into an upper and a lower chamber, a circulating system including heat exchange units connected to the extremities of said upper chamber, a baffle arrangement positioned in an intermediate portion of the upper chamber, means for circulating liquid from the lower extremity of the upper chamber through the circulating system to the upper extremity of the chamber whereby the returning liquid flows downwardly by gravity over the baffle arrangement to release entrained gases therefrom, means for connecting said lower chamber to said circulating system for removing liquid therefrom, means responsive to the liquid level in the upper chamber for regulating the flow of liquid from the lower chamber to the circulating system, and means for placing the upper chamber and the lower chamber under a vacuum pressure.

3. A deaerating system of the character described comprising a container, a partition for dividing the container into a deaerating chamber and a liquid storage chamber, means for circulating liquid through a system including a plurality of heat exchange units and through the deaerating chamber, means carried by the partition for communication between the deaerating chamber and the storage chamber, whereby liquid reaching a predetermined level in the deaerating chamber will drain into the storage

chamber, and means responsive to the liquid level in the deaerating chamber for connecting the storage chamber with the circulating system for supplying liquid thereto.

4. A deaerating system of the character described comprising a container, a partition for dividing the container into an upper deaerating chamber and a lower liquid storage chamber, an overflow pipe extending upwardly from the partition into the deaerating chamber whereby liquid reaching a predetermined level in the deaerating chamber will overflow into the storage chamber, means for circulating liquid through a system including a heat exchange unit and through said deaerating chamber to release entrained gases therefrom, and means responsive to the liquid level in the deaerating chamber for connecting the storage chamber with the circulating system to supply liquid thereto.
